APPARATUS AND PROCESS FOR PREPARATION OF SEED COKE FOR FLUID BED COKING OF HYDROCARBONS

Worth William Boisture, Byron Victor Molstedt, Richard Franklin Stringer, and Lindsay Ira Griffin, Jr., Baton Rouge, La., assignors to Esso Research and Engineering Company, a corporation of Delaware

Application September 5, 1956, Serial No. 608,162

5 Claims. (Cl. 202—25)

The present invention relates to an apparatus and process for preparation of seed coke for fluid bed coking of hydrocarbons such as residual oils and the like. More particularly, the invention relates both to an apparatus and a process for providing the requisite small particles of coke to serve as nuclei for deposition of coke formed in the process. One object of the invention is to replace larger coke particles which are withdrawn from the system as product coke with smaller particles so as to keep the total number of particles in the system approximately constant. The invention includes means for breaking up large coke particles so that the growth in average particle size which occurs by coke deposition is compensated for by the withdrawal of large coke particles and replacement with an equivalent number of small coke particles. The invention relates further to an efficient and effective method of breaking up the large particles and preferentially returning small particles to the coking zone to serve as "seed" coke. This application is a continuation-in-part of application Serial No. 403,218, now abandoned, filed January 11, 1954 by the present inventors.

In the conversion of hydrocarbon oils, especially petroleum crude oils, it has been the practice for many years to distill off the more volatile fractions and to subject the heavy residues to thermal cracking to obtain as much motor fuel and other low boiling fractions as possible. In all these prior processes considerable quantities of heavy, viscous, residual oil or pitch has been produced. While this pitch is usually of relatively low value there has normally been a fair market for it, but this has declined in recent years. Hence it is desirable to convert the heavy residua to more valuable products.

Among various processes which are used for coking, the fluid solids process, recently developed, appears to be among the most efficient and it promises to be most successful. In this process, as is well known, a mass of fluidized preheated solids, such as sand, metal particles, clay, alumina, beads, and especially coke particles formed in the process, is used to supply the necessary heat for coking or conversion of the residuum. A major proportion of the residuum normally is converted to gas oil and other fractions of higher volatility than the feed. A minor proportion of the feed is converted to coke. Various solids such as those mentioned above can be used to supply the heat of conversion. Since coke is a product of the process, however, it is usually preferred. The present invention pertains particularly to means and methods for controlling the particle size of the circulating solids, especially those consisting entirely or largely of coke, to maintain a continuously operable process. It will be understood that even when solids other than coke are used to start the coking operation they become coated with coke to such a degree that particles withdrawn from the coking system are composed of coke to a large extent.

It has now been discovered that a fluid coking system using coke particles as the heat carrying media can best be kept in balance by continuously keeping a rela-

2

tively constant number of coke or other coking nuclei particles within the system. These particles grow constantly by the deposition of layers of heavy oil and its conversion to coke layers on the initial or nuclei particles in the coking zone. Moreover, some particles adhere to each other and unite to reduce the total number of discrete particles. It is found necessary to withdraw from the system the large coke particles and to replace them with an equivalent number of small particles, to keep both the total number and the size distribution in equilibrium. The small particles which serve as nuclei for new coke deposition may be considered "seed" coke, and this term will apply hereinafter even when some of the particles, initially at least, are composed of other materials than coke, as indicated above.

In the catalytic cracking of hydrocarbons where fluidized masses of finely divided solids are used as catalysts, the total number of particles in a given system can vary widely. The catalyst particles, on the average, may be much finer than the coke particles which are used in the fluidized solids coking process. Moreover, the catalyst is not withdrawn from the system as a product but the coke is merely burned therefrom and the catalyst is reused, as long as it retains its activity. Hence there is no problem of removing a solid product and keeping the number of particles in the solids inventory substantially constant. The particle size distribution may change gradually until corrected by periodic addition of fresh solids. In coking there is normally no such periodic addition.

The production of the seed coke or other particulate nuclei to serve as nuclei for the production of larger coke particles may be accomplished, in a preferred embodiment, by projecting the relatively large particles, or a portion of the solids stream, at high velocity. Impact against each other at high velocity is effective and impact against a hard, target surface is also effective to break them up into smaller particles.

While the degree of breaking up solid particles in the system may be varied somewhat the ratio of average diameter of the broken or seed coke particles to the average particles in the system is preferably not less than about $\frac{1}{5}$ nor more than about $\frac{1}{3}$. It appears, moreover, that particles of about $\frac{1}{5}$ average diameter are deemed to be about as small as can be handled efficiently for purposes of the invention. Particles of fines are rapidly lost in overhead flue gases, for example. Attrition to smaller sizes also consumes power without compensating improvement in the process. On the other hand, seed coke particles only slightly reduced in diameter, e. g., to $\frac{1}{3}$ of the average particle diameter in the coking system, are about as large as can be tolerated economically, a rapid turnover or circulation of coke being required when size reduction is only minor.

It will be seen, therefore, that the invention involves the broad aspects of maintenance of a balanced system with a relatively constant number and size distribution of particles as well as a relatively constantly circulating mass of heat carrying and coke-accepting particles even though these particles tend to grow in the system. It involves also a narrower aspect of method and apparatus for providing within the system the small nuclei or seed particles to replace the large ones that are withdrawn.

The invention will be more fully understood by reference to the attached drawings which show alternative methods for the production of the small or seed coke particles and various aspects thereof.

Referring to the drawings,

Fig. 1 shows in elevation and partly in section a coking apparatus or vessel which may be a coking reactor represented diagrammatically, in which coke or other solids

within the system are converted to seed particles in the vessel;

Fig. 2 shows another seed forming or impact system where the necessary small particles are provided by impelling larger particles forcibly against an impact target element in an elutriation zone from which the small and large particles, respectively, may separately be withdrawn;

Fig. 3 shows still another system wherein small or seed coke particles are produced by the action of opposed jets entraining larger particles and striking them against each other in a relatively disperse section of a conveyor or transfer line in a coking system;

Fig. 4 shows a diagrammatical elevation of the major essential elements of a coking system including a modified form of the present invention;

Fig. 5 is a graphical showing of the effect of particle velocity and apparatus characteristics on the efficiency of seed coke production;

Fig. 6 is a graph showing particle size distribution in a coking system where there is substantially no segregation of larger particles for coke product;

Fig. 7 is a graph showing particle size distribution where a constant inventory of solids is maintained by withdrawing only the coarse particles as product coke.

Referring in detail to the drawings, a reactor vessel 11 which may be of any suitable shape and size is shown diagrammatically in Fig. 1. An attrition or grinding system is shown inside this vessel. Coke particles or equivalent fluidizable heat carrying solids are brought into vessel 11 by any suitable means such as a line 13 leading from a heater or burner, not shown, where the particles are raised to a suitable coking temperature, for example, between 900 and 1250° F. more or less. The particles may be brought in through line 13 either in fluidized state or in a disperse state by means of an aerating or lifting gas or vapor such as steam, as is well known in the art. It will be understood that the attrition mechanism may be placed in or connected to a transfer line, a reheater or burner, or some other part of the system, as desired. See Fig. 4 and its description below. Hence, Fig. 1 is only exemplary.

Fluidizing steam or other gasiform fluid, which may include hydrocarbon vapors, is introduced into the vessel 11 in a lower portion thereof to maintain the necessary fluid motion of the solid particles within the bed 15 which is established in the vessel 11. Under balanced conditions this bed forms a more or less stable upper level or interface 17. In the present case advantage is taken of the steam or other gas used for fluidizing the solids, to break up or cause attrition of the solid particles and to thereby furnish the seed coke or related solids referred to above. As shown herein, jets of steam are introduced through inlets 19 and 21 respectively, and are directed through venturi orifices or nozzles 23 and 25 towards each other. Where a target of solid material is used, they may be directed against the opposite sides of a steel plate or the like, 27. The configuration and arrangement of the venturi members is such that the solid particles of coke, or equivalent, surrounding the members 23 and 25 are drawn into and through the venturis by the high velocity jets of steam or gas and are impacted with considerable force against each other and/or the plate 27. The spacing between the members 23 and 25 and the plate 27 respectively is such that the jet of steam plus particles flows upwardly and downwardly through the openings, as indicated above, with the result that these spaces are relatively clear and impact against the plate is relatively unimpeded. As the solids become spent by cooling and/or becoming coated with new coke layers they are withdrawn through a line 29. From here they may be returned to the burner. Oil feed may be introduced through suitable nozzles 31 as is well known in the art. As will be shown below, the velocity of the impelling jets and the length of the accelerating tubes or nozzles have important effects on the efficiency of the grinding or breaking up of the particles.

It will be understood that particles, e. g. of coke, are continuously withdrawn from the vessel through line 29 and continuously returned thereto through line 13.

The volatile fractions produced by coking are withdrawn from the reactor vessel through a suitable gas-solids separator 35, the separated solid particles, i. e. of coke, being returned to the bed 15 through the conventional solids return line 37. The vaporous and/or gaseous products are taken overhead to a suitable recovery system through outlet line 39.

In the system of Fig. 2, a stream of solid particles having a larger average size than is desired within a coking reactor, may be fed through an inlet 51 into a conduit 53. A stream of fluid such as steam or gas is passed through conduit 53 at sufficiently high velocity to cause fracturing of the particles entrained therein when they strike each other or any hard impact surface. This velocity may be from about 100 to 1000 feet per second, the range of 200 to 600 usually being preferable. The solids entering through line 51 are picked up in the high velocity gas stream or jet coming through line 53, and carried forcibly against an impact target 55. The impact target, as shown in Fig. 2, is formed with a concave impact surface. With the proper configuration the particles striking this surface rebound convergently in such a manner so as to maintain a cushion of particles on the concave face of the plate 55. With this arrangement most of the impact force is spent on the particles rather than on the impact plate so that the latter is not rapidly worn away by abrasion. However, in some cases a certain amount of wear is not objectionable, since this member can readily be replaced and impact against a flat hard surface produces more efficient grinding in terms of steam consumption. Where wear is not objectionable a flat plate or target such as the plate 27 in Fig. 1 may be used. Conversely, a plate or target of double concave type could replace the plate 27 in Fig. 1 if desired.

The impact plate 55 is located in a relatively enlarged conduit section 57. This conduit, however, is not of sufficiently large cross-section to permit dense phase fluidization of the solids therein. Preferably, the particles are entrained in an upwardly flowing gas stream, i. e., in disperse phase, though this is not always necessary. The conduit 57 connects with an enlarged elutriating section 59. The latter is of sufficient cross-sectional area that the gas stream is inadequate to carry the heavier or larger particles. All the particles, fine and coarse, emerge from conduit 57 under the impulse of the fluid stream through line 53 but the heavier particles drop into an annular area 60 outside conduit 57 and inside the elutriator 59. A grid member 61 is placed across a lower part of the annular area 60 of elutriator 59 to separate the heavy particles from a chamber 63 within which a fluidizing gas may be introduced through a line 65.

Thus, as particles emerge from the top of the section 57 their velocity is immediately reduced and heavier particles fall back on to or toward the grid 61. The fluid, e. g., steam or hydrocarbon gas, introduced through line 65, makes a fluidized bed of them. The velocity of the aerating gas in the elutriator 59, is sufficient to elutriate therefrom any finer particles produced by impact against the plate 55. Most of the fines are carried overhead directly from conduit 57. The fine particles pass overhead directly from conduit 57. The fine particles pass overhead out of the elutriator 59 through an outlet 69. From here they may be returned to the coking system. The coarser fluidized coke particles in bed 60 may be withdrawn from the system through an outlet line 71 controlled by a valve 74. The coarse particles in bed 60 are often partially broken and it is usually advantageous to recycle at least part of them to the grinder or attritor 53, 55. This may be done by connecting line 75, or a branch thereof, to line 51 as will be obvious.

Still another arrangement is shown in Fig. 3 wherein solids are fed by lines 80 to two opposed jets 81 from

whence they are driven into an enlarged section 83. The particles in the respective jets are broken by mutual impact at high velocity. The particles, after impact, are swept around and upwardly as shown by the arrows, under the impelling effect of a fluid stream and guidance of the housing 84, 85. Here they are preferably in relatively disperse phase. Under the impelling gas stream they flow upwardly, still in disperse phase, through a conduit 87 into a disperse zone in the upper part of an elutriating vessel 89. The heavier particles fall by gravity onto a grid 90 supported in the annular space between inlet conduit 87 and the outer walls of vessel 89. A fluidizing gas is fed into the space below the grid by a line 91. It passes through the grid to form a fluid bed 92 of the coarse solids which disentrain by gravity from the upflowing stream emerging from conduit 87. The upper lever of this bed is indicated at 93. A draw-off line 94 equipped with valve 95 is provided and the coarse solids may be recycled to attritor jets 81, or withdrawn as coke product, or taken to a burner.

Referring now to Fig. 4, there is shown a fluid bed coking system, including a burner or heater, with an attritor elutriator fitted into the transfer lines. The coking vessel 101 is of the conical or tapered type. Feed, suitably pre-heated, is introduced through manifold feed lines 103, 105 and a plurality of nozzles 107, 109 into a bed of pre-heated, heat-carrying fluidized solids, specifically coke particles of a size between about 40 and 500 microns average particle diameter. These particles normally are preheated to a temperature above 1000° F., up to 1200° F. or more, in a burner vessel 111. The hot particles flow from the burner through a standpipe 113, a relatively sharp U-bend 115, and a steep riser 117, under control of valves 119, 121. The spent coke particles from reactor vessel 101 flow through a coarse screening device 123 in a stripping section or zone 125, down into a standpipe 127, a relatively sharp U-bend 129, a steep riser 131 with a control or cut-off valve 133, into an inlet 135 to a deflector 137 in the burner vessel 111.

Stripping gas, such as steam is introduced into the stripping zone 125 through a line 141. Large lumps or agglomerated particles of coke, and other product coke, if desired, may be removed from the reactor vessel through outlet 143 under control of valve 145.

As coke withdrawn from the reactor flows downwardly, it may be aerated or partly aerated and impelled through the angle bend (sharp U-bend 129) by a jet of steam or the like introduced through a line 147. Other aerating lines 149, 151, 153, 155 and 157 are provided for lifting the coke into the burner vessel. Air may be fed into some or all of these to start combustion as the coke is flowing into the burner. The burner vessel preferably has a combustion chamber or starter at the bottom, indicated at 159, to which air and/or fuel may be fed through line 161 for initially heating up the burner. Air and/or fuel may continue to be fed to the burner from this source if desired.

The hot coke, or part of it, may be withdrawn as product from the burner side of the vessel, if desired, through an outlet 163 under control of a valve 165. It may be cooled as withdrawn by stripping it with a stream of water or steam introduced through line 167. By operating the burner at suitably high temperature, water gas may thus be generated, the temperature of product coke and/or coke returning to the coking reactor thus being brought down to the desired levels. The combustion and/or combustible gas from the burner passes through a conventional solids separator 169. Entrained solids are returned to the fluid burner bed 171 through solids return line 173. The gases, substantially free of entrained solids, pass overhead through an outlet line 175 under control of valve 177 to a suitable heat recovery and/or disposal system. The solids returning from the burner to the reactor are suitably aerated and buoyed up by steam, hydrocarbon gas, or other inert gasiform fluid introduced

through aerating taps 181, 183, 185, as is well understood in the art. Because the solid particles are much coarser, on the average, than the solids used in older fluid bed systems, e. g. than catalytic cracking catalysts, they tend to become deaerated quickly and lose buoyancy. For this reason the risers 117 and 131 should be quite steep, at least 50° from horizontal and preferably 60° or more.

The coke from the reactor is taken to a grinder 190, flowing up through line 191 under the driving force of a stream of gas injected by line 151. The line 151 may project through or partially through the riser 131, or other jet means may be introduced into line 191, above or below control valve 193, so as to drive the coke particles upwardly at high velocity, 100 to 1000 feet per second to grind them. The high velocity jet itself is an effective grinder but it may be aided by a target plate 195 arranged within an enlarged conduit 197. The arrangement is substantially identical with that of Fig. 2.

The coke particles, broken, partly broken, fine and coarse, are all carried upwardly into elutriator vessel 199 where the fine particles continue to be entrained and carried overhead by the impelling gas stream through outlet 201. From here they may pass through valve 203 and line 205 into riser 117 and are returned to the coker. Alternatively, the fine particles, or part of them, may be passed to the burner through line 207 and valve 209, a propelling jet of suitable gas being provided as indicated at 211.

The heavier particles fall back into an annular area 213 onto a grid 215 through which a fluidizing gas supplied by line 217 is flowing upwardly. The fluidized particles, which are coarser, may be withdrawn through line 219 under control of a valve 221 and recycled to line 191 by a lifting or propelling fluid injected by a line 223. From line 191 they may be recycled to the attritor or grinder 195, which is often desirable because partially cracked particles usually break up more easily than uncracked particles, or they may be fed back into riser 131 to go to the burner. If desired, product coke may be withdrawn at 225.

The vapor products from the coker pass overhead through a conventional solids separator 221 with solids return line 223 and product outlet line 225.

It will be understood that the grinding of coke particles to reduce their size for reuse is disclosed in a patent to Kuhl No. 2,339,932. The present invention involves not only an improved grinding technique but also the concept, stated in part above, of constantly replacing large coke particles withdrawn from the system with an equivalent number of small or "seed" coke particles, to keep the coke receiving or deposit surfaces substantially constant in total area and keeping the total coke mass or inventory in the coker substantially constant.

The nature of the coking process is such that coke is being formed constantly and deposited on the solids which supply the heat for conversion. These particles grow in average diameter by accretion of coke layers at a rate that is substantially independent of particle size. That is, whether a particle has a diameter of 100 microns or 10 microns, growth by 10 microns takes substantially equal time, on the average. The 100 micron particle grows to 110 microns while the 10 micron particle grows to 20. The ratio of increase in weight is greatly different. The larger particle increases about 33% while the smaller one increases about 700%.

Operation of a large scale pilot plant using fresh Discoke of high ash content, and analysis of the gradually lowering ash content as particles grow gave clear proof that coke is deposited as stated above. Coke was deposited in direct proportion to surface area, i. e., in layers of equal thickness during a given time, regardless of particle size.

When coke is burned from the particles, it is also removed in layers of substantially uniform thickness per unit of time, quite regardless of particle size. A careful

study of burning particles of widely different sizes showed clearly that the weight of coke burned was directly proportional to surface area.

Hence, both product coke deposition and coke burning, the increase or reduction in diameter, proceeds at a uniform rate independent of particle size. Theoretically, then, if all the coke produced were burned to supply heat and the rate of burning were precisely the same as the rate of deposition, addition of seed coke would not be necessary. The system would stay in equilibrium. In practice, however, only about 20% or less of the coke produced is burned to supply heat requirements, even with the lowest coke-producing oils suitable for coking. Losses of fines from the system are normally considerably larger than any natural attrition and it may be said that in all cases some grinding is essential.

In a typical large scale pilot plant operation, coking approximately 100 barrels per day of heavy residuum, product coke was withdrawn at a rate that varied from 1300 to 2200 pounds per day to keep the inventory constant. For five days fine seed coke (100 to 200 mesh) was added at a rate varying between 100 and 500 pounds per day. Frequent sampling of the circulating solids showed that the circulating coke gradually was becoming finer in particle size.

At the end of the fifth day, about 53% by weight of the coke would pass through a 100 mesh (150 microns) sieve. Thereupon the addition of seed coke was discontinued. Within about 2 days particle size had increased so that only 18% of the coke would pass the 100 mesh sieve. 80 mesh and coarser jumped from 20% to 50 in the same 2 day period. The unit would very shortly have become inoperable if it had continued in operation without seed addition.

Operation of commercial cokers shows clearly, moreover, that sufficient fine solids must be included to permit some entrainment of fines overhead. They serve as scouring agents to keep the apparatus clean. Not only are they effective scouring agents but they add heat capacity and they provide surface for deposition of coke by the overhead vapors, helping to keep it off the apparatus.

In order to control particle size, additions of small or "seed" particles constantly or essentially constantly is required. Proportions larger than about 5% by weight of 200 mesh-material (smaller than about 75 microns) cannot be kept in the system because of entrainment. On the other hand, if there are more than about 20% by weight of particles larger than 48 mesh (about 295 microns) the system operates very roughly, slugging occurs in the transfer lines and bumping in the fluid bed because of erratic fluidity. These limits, therefore, are quite critical. Further, by keeping average particle size in the system below 300 microns, the maximum operable feed rate of the unit can be increased.

As shown in Figs. 6 and 7, the particle size distribution required to maintain equilibrium in a stable system depends to a very important extent on the degree of segregation of large particles in the product coke. With no segregation, for example, a much wider distribution is found than with complete segregation of the largest particles as product.

In Fig. 6 the ratio of D to D_0 is the ratio of diameter of a given size of particle to the diameter of the seed coke. The various curves are based on various grinding ratios. In the top curve, $M_C=20$ is the ratio of product coke by weight to the ground seed coke recycled to the reactor. That is, 5% as much coke is ground as is withdrawn as product. If this coke were ground only to a particle size, say, of 100 mesh (about 150 microns) 20% of the coke would have a particle size of over 900 microns (6.2 times 150) which cannot be tolerated, as mentioned above. Hence an upper limiting factor on seed particle size when there is no elutriation to concentrate coarse particles in the product coke, is determined by dividing the

48 mesh coke size (approximately 300 microns) by the ordinate of the 80% line with each curve. In the case of the $M_C=20$ line it is approximately 300/6.2 or a little less than 50 microns. But the system cannot tolerate more than 5% of less than 75 micron material hence curve $M_C=20$ is inoperable. Also, on the $M_C=10$ curve, seed particle size would have to be below 70 microns. This small size seed coke would be lost from the system. Without elutriation or segregation of coarse particles in the product coke, only the two lower curves, $M_C=4$ and $M_C=2$ are operable. The limit is indicated approximately by the dotted line L.

With elutriation to segregate coarse particles in product coke, all of the conditions shown are operable. Here

(Fig. 7) the diameter ratio of particles at any point on a curve away from the origin is generally lower than in Fig. 6. Even so, however, constant seed coke replenishment is necessary but its rate can be much lower. In practical operations, about 3% of seed coke based on product coke is the minimum requirement. The particle size ratio limits mentioned earlier in this specification of $\frac{1}{6}$ to $\frac{1}{4.3}$ will be seen to lie fairly near the midpoints of curves $M_C=20$ of Fig. 6 and $M_C=2$ of Fig. 7, respectively. They are indicated as x and y.

In practice, seed coke is not ground to a uniform size and the factors given above are not precisely applicable to average particle sizes of grinding but the relationships are reasonably approximate, even when the spread of seed particle sizes is rather broad.

By balancing the grinding and the selection of large particles to be withdrawn to keep the system in equilibrium maximum efficiency and continuing stable operation are obtained.

As suggested above, still another feature of this invention relates to the discovery that there is an optimum jet velocity and an optimum jet apparatus design for high efficiency in grinding or attriting the coke. In order to study these factors, various jet velocities and various lengths of accelerating tubes were tested in impacting the solids against a steel target plate. The arrangement of the test nozzles and target were substantially as in Figs. 1 and 2, that is, the coke was fed into a high velocity gas jet, and the length of the tube from solids inlet to the tube outlet was measured as the length of accelerating tube.

The coke tested had the following particle size distribution before the attrition or grinding tests:

Table I

50	Tyler Mesh	Min. Particle Size, Microns	Wt. Percent on Screen
35		417	0.2
48		295	10.5
60		246	42.7
80		175	87.0
100		147	95.4

At a gas inlet velocity (at the point where coke was introduced into the accelerator tube) of 145 feet per second there was only a small amount of attrition. Particles smaller than 160 microns (about 90 mesh) increased by only 2.2% of the total mass. Particles larger than 240 microns (about 60 mesh) decreased by the same amount.

At a gas velocity of 208 feet per second, there was an increase of 9% of the total weight material of less than 200 microns (about 68 mesh) and a decrease of 9% in coarse material larger than 240 microns. At 246 feet per second there was an increase of 21 weight percent of material smaller than 200 microns average diameter.

The tests showed that there is an increase in all cases of material smaller than 200 microns and a decrease of material larger than 200 microns. They showed also that in the gas velocity range of 200 to 250 feet per

second there is no apparent material difference in selectivity to fine material smaller than about 80 microns. At 246 feet per second 28% of the increase by weight of particles finer than 200 microns was in particles below 80 microns. At 208 feet per second, 22% were smaller than 80 microns (about 180 mesh).

A desirable "seed" coke particle size appears to be in the general range of 50 to 200 microns. At 200 feet per second the material passing through a 100 mesh screen (about 150 microns) increased by 2%. At 250 feet per second it increased 14% by weight.

Fig. 5 of the drawing shows graphically the relation between jet velocity and efficiency of grinding, in terms of horsepower hours required to produce a ton of seed coke (through 100 mesh—i. e., below about 150 microns). At 230 feet per second the power required, in an 8 inch accelerator tube, to produce one ton of seed coke was only 48 horsepower hours. At 160 feet per second power requirements were 115 horsepower hours.

Fig. 5 also shows the effect of the length of accelerator tubes. The 8" tube was much more efficient than either a 4" tube or a 24" tube in the diameters tested, and the diameter in test apparatus, 2 mm. vs. 4 mm., appeared to make no measurable difference. In larger scale apparatus it appears that the same is approximately true, proportionately. For small diameters the accelerator tube should be between about 4 and 24 inches long, with about 8" being the optimum for efficiency. Apparently the 4" tube is too short to bring particles up to gas velocity, due to slippage. The 24" tube showed too great a pressure drop, due to friction, for efficient operation of a 4 mm. tube. With larger diameters, optimum lengths are proportionately greater.

Within the range of 0.3 to 1.0 pound of coke per s. f. c. of gas, the solids loading rate appeared to be about optimum and variations were narrow. At a loading rate of less than 0.1 pound per s. c. f., the power requirements increased very greatly. Results are indicated in Table II, using the 8" accelerator tube nozzle.

Table II

Loading, # Coke/s. c. f. Gas	Vel. of Gas in Accel. Tube	H. P. Hr./Ton Coke Thru 100 Mesh
0.08	300	428
0.38	246	48
0.61	255	47

Similar results were obtained, using a narrow size range of coke particles (48-60 mesh, 249-295 microns) for feed. The correlation of gas velocity vs. efficiency was substantially unchanged. Power requirements were slightly higher than for the wider size range coke of Table I. Note that power requirements level off and become relatively constant at 260 to 300 F. P. S. and above.

By comparison, a ball mill grinder required 97 horsepower hours power input to grind a ton of coke, of about the same size distribution, to pass a 100 mesh screen, roughly or nearly double the power requirements for a steam jet. Aside from operating costs, investment costs for a ball mill are much higher. The impact attritor system is even more efficient operating on relatively large and agglomerated coke particles. With agglomerated coke of 20 to 35 mesh (400 to 800 microns) 96.7% by weight was reduced in particle size in a lightly loaded jet at 250 feet per second. By comparison, a 48 to 60 mesh sample (246 to 295 microns) showed size reduction of only 26.2% in one pass.

As mentioned above, it has been found advantageous to recycle broken coke particles of large size to the accelerating nozzle. Using an 8" accelerating tube of 4 mm. inside diameter with a loading of 0.25 pound per s. c. f. gas at 200 feet per second, 94 horsepower

hr./ton was required to produce coke passing 100 mesh. When the coke was recycled at 200 feet per second the power requirement was cut to 46 horsepower hr./ton. The discharged material from the two runs showed the following particle size distribution:

Table III

Wt. on Mesh	Run A—Original Coke	Run B—Recycle
35	5.6	0.9
42	53.4	29.5
48	71.4	50.5
60	80.5	61.2
80	89.8	73.6
100	93.6	80.7
150	99.2	88.2
200		93.4
325		97.2

Hence, the recycle of the coarse coke from line 75 to line 51 in Fig. 2, from line 94 to line 80 of Fig. 3, or through line 219 in Fig. 4, appears to be highly advantageous as regards grinding efficiency.

In elutriating the fine particles from a bed or mass of ground or attrited coke, efficiency of separation may be increased by packing the bed with Berl saddles, Raschig rings, or the like, as will be understood by those skilled in the art. The beds 60, Fig. 2, 92, Fig. 3 and 213, Fig. 4 may be so packed, if desired, so that the finely divided solids may be more effectively separated from the coarser solids.

Various improvements and modifications, such as the use of cyclones or other size separation devices instead of elutriators, will suggest themselves to those skilled in the art and it is intended, in the claims which follow, to cover such, so far as the state of the art permits.

What is claimed is:

1. In the process of coking heavy hydrocarbon oils by contacting them with a fluidized mass of preheated coke particles, wherein the coke particles are continuously passed through a fluidized coking zone to grow by accretion of coke therein and at least part of said particles are continuously reheated and recycled through coking zone inlet and outlet lines, the improvement which consists in maintaining a substantially constant mass, number and size distribution of coke particles in the total system by constantly withdrawing relatively large coke particles from the system so as to keep the particles of over 300 microns diameter generally below about 20% of the weight of the total coke in the system, and constantly replacing the withdrawn particles by a substantially equal number of smaller particles whereby the accretion of coke on the particles is compensated for and the coking zone is maintained in fluidized condition.
2. Process according to claim 1 wherein the smaller particles in the system do not exceed about 5% by weight of particles below 75 microns average diameter.
3. The process of coking hydrocarbon oils which comprises impelling particles of coke at a velocity of 150 to 1000 feet per second against solid target material so as to produce small particles of seed coke size, elutriating said small particles from larger particles, passing said small particles to a coking reactor, feeding oil into contact with said small particles to coke said oil and deposit coke upon said particles, thereby causing said particles to grow, and withdrawing from the system large coke particles at a rate adjusted to keep the total number and mass of coke particles in the system substantially constant, said impelling, elutriation of small particles and withdrawal of larger particles being so controlled as to break up at least 3% of the solids, based on the weight of those withdrawn, whereby not more than 20% by weight of solids in the system are of greater size than about 300 microns average diameter.
4. The process of claim 3 wherein not more than

5% by weight of the solids in said coking system are smaller than 75 microns average diameter.

5. An improved method for pyrolyzing heavy hydrocarbon feed in a fluid bed at high feed rates while preserving smooth fluidization, which comprises, maintaining a mass of inert particles at a reaction temperature, introducing fluidization gas through said mass so as to form a fluid bed, contacting hydrocarbon feed with said inert solids thereby converting said feed to lighter hydrocarbon products which are removed overhead, and carbonaceous residue which constantly deposits on said solids, withdrawing a portion of said carbonaceous coated solids, attriting at least 3 weight % of said withdrawn solids, elutriating said attrited solids and returning thus treated solids to said reaction mass so as to maintain a constant mass, number and size distribution of solids therein, said size distribution being characterized by less than 20 weight percent of said solids having a diameter greater

than 300 microns and less than 5 weight percent having a diameter below 75 microns.
